UNITED STATES PATENT OFFICE.

FREDERICK W. SMITH, OF PORTLAND, OREGON.

DESIGN FOR A SET OF PLAYING-CARDS.

56,482.

Specification for Design.

Patented Oct. 26, 1920.

Application filed October 20, 1919. Serial No. 332,124. Term of patent 7 years.

To all whom it may concern:

Be it known that I, FREDERICK W. SMITH, a citizen of the United States, residing at Portland, in the county of Multnomah and State of Oregon, have invented a new, original, and ornamental Design for a Set of Playing-Cards, of which the following is a specification, reference being had to the accompanying drawing, forming part thereof.

The figure is a plan view of the playing cards.

I claim:

The ornamental design for a set of playing cards, as shown.

FREDERICK W. SMITH.

Witnesses:

ALFRED E. SMITH,
A. M. HUMPHREYS.
